C. J. DEL MARMOL

ADJUSTABLE COMBINED SOUND BOX AND RADIOPHONE

Filed Aug. 1, 1924

INVENTOR
Charles J. Del Marmol
By W. W. Williamson Atty.

UNITED STATES PATENT OFFICE.

CHARLES J. DEL MARMOL, OF PHILADELPHIA, PENNSYLVANIA.

ADJUSTABLE COMBINED SOUND BOX AND RADIOPHONE.

Application filed August 1, 1924. Serial No. 729,470.

My invention relates to new and useful improvements in an adjustable combined sound box and radiophone, and has for its primary object to produce a structure combining a radio loud speaker unit with a sound box of a talking machine and to so arrange the parts that the magnet element is adjustable relative to the diaphragm in order to regulate the sounds produced by the radio loud speaker unit.

Another object of this invention is to provide a radio receiver, such as a loud speaker unit and the like with a simple and effective means for adjusting the magnet element relative to the diaphragm.

With these ends in view, this invention consists in the details of construction and combination of elements hereinafter set forth and then specifically designated by the claims.

In order that those skilled in the art to which this invention appertains, may understand how to make and use the same, I will describe its construction in detail, referring by numerals to the accompanying drawing forming a part of this application, in which:—

Fig. 1, is a sectional elevation of an adjustable combined sound box and radiophone embodying my improvements.

Fig. 2, is an inner face view of the radio receiver magnet element and its component or corelated parts.

In carrying out my invention as here embodied, 2 represents the casing of a reproducer or talking machine sound box of any desirable or well known construction but more particularly shown as embodying certain features covered by my patent applications Serial Number 676,488, filed November 23rd, 1923 and Serial Number 713,472, filed May 15th, 1924, and in this casing is suitably mounted the diaphragm 3 of any well known or approved construction produced from any suitable material and constructed so as to be attracted by magnets as will be hereinafter more fully explained. Well known forms of diaphragms suitable for this use are described in United States patents to A. M. Dolbear, No. 199,041, January 8, 1878 and Alexander G. Bell, No. 201,488, March 19, 1878. Connected with the diaphragm is a stylus mounting 4 to receive the stylus 5 which coacts with a talking

machine record so as to transmit the vibrations to the diaphragm.

In one face of the casing is an opening 6 for connection with a suitable horn of a talking machine while in the opposite face of the casing is another opening 7 for the insertion of a magnet element 8 which with the diaphragm 3 makes up or completes the radio receiver such as a loud speaker unit and this element includes the electromagnets 9, the pole pieces 10 of which are adapted for coaction with the diaphragm 3 to cause the usual vibrations to be set up in said diaphragm due to the pulsations of electrical energy passing through the magnets as is well understood in the art. The body portion or container 11 of the electromagnets is of circular formation, as plainly shown in Fig. 2, and is exteriorly threaded as at 12. It is to be understood that the container or body 11 of the magnet element is of less diameter than the opening 7 so as to freely pass in and out of said opening and in order to move said magnet element relative to the diaphragm 3 in order to regulate the distance between the electromagnet and the diaphragm I provide an adjusting member 13 which is also of circular formation and interiorly threaded for threaded engagement with the magnet element 8. Said adjusting member 13 is of sufficient length to be readily gripped by an operator for rotation thereof to move the magnet element, it being understood that the adjusting member 13 is rotatably mounted on the casing of the reproducer while the magnet element is held against rotation but permitted to move to and fro. In order to accomplish this the adjusting member 13 is provided with an annular exterior flange 14 which rests against the outer face of the reproducer casing and held against displacement by a collar 15 having holes 16 therethrough for the reception of suitable fastening devices such as screws 17 passing through the collar and threaded into the reproducer casing. Said collar 15 includes an inwardly projecting flange 18 which overlaps the flange 14 of the adjusting member thereby permitting rotation of the latter while preventing lateral or longitudinal movement thereof. The magnet element 8 is prevented from rotation while permitting a longitudinal movement thereof by forming

a key way 19 in the body or container of said magnet element while with said key way registers a key 20 fastened within the opening 7 of the reproducer casing in any suitable manner.

The magnet element 8 is provided with the necessary binding posts, one of which is shown and designated by the numeral 21 for connection of the necessary conductors of the magnet element which conductors lead from the radio receiving set.

From the foregoing description it will be obvious that if the device is used in connection with a talking machine record the sounds will be reproduced by the diaphragm through the medium of the stylus and the stylus mounting and said sounds carried off through the opening 6 in the well known ordinary manner but when it is desired to use the same device for reproducing radio broadcasts the pulsations of electrical energy set up in the electromagnets will vibrate the diaphragm 3 and cause the reproduced sound to be transmitted through the opening 6 to the horn with which the device is connected. As it is oftentimes desirable to regulate or modulate the sounds produced by the radio receiver or loud speaker unit this may be readily accomplished by rotating the adjusting member 13 in the desired direction for moving the magnet element 8 in or out which will change the distance between the electromagnet pole pieces and the diaphragm 3 and thereby increasing or decreasing the strength of the transmitted sounds.

Of course I do not wish to be limited to the exact details of construction as herein shown as these may be varied within the limits of the appended claims without departing from the spirit of my invention.

Having thus fully described my invention, what I claim as new and useful is:

1. The combination with a reproducer including a casing having openings in opposite faces, one of which forms a communication between the interior of the reproducer cas-

ing and a horn, a diaphragm and a stylus mounting, of a magnet element located in the other opening of the reproducer casing for coaction with the diaphragm, an adjusting member having threaded engagement with the magnet element, means to rotatably mount said members on the reproducer casing, and means to prevent rotation of the magnet element while permitting movement thereof relative to the diaphragm.

2. In a device of the character stated, a casing having an opening therein, a diaphragm within said casing, a magnet element projecting through the opening for coaction with the diaphragm, said magnet element including an exteriorly threaded body, electromagnets and means for connection with the audio circuit of a radio receiving set, means to prevent rotation of said magnet element, and means rotatably mounted on the casing and having threaded connection with the magnet element whereby when said adjusting member is manually rotated the magnet element is adjusted relative to the diaphragm.

3. In a device of the character stated, a casing having an opening therein, a diaphragm within said casing, a magnet element projecting through the opening for coaction with the diaphragm, said magnet element including an exteriorly threaded body, electromagnets and means for connection with the audio circuit of a radio receiving set, means to prevent rotation of said magnet element, an adjusting member having threaded connection with the body of the magnet element, and a collar secured to the casing and coacting with the adjusting member to rotatably mount said adjusting member on said casing, said adjusting member adapted to be manually rotated for moving the magnet element relative to the diaphragm, as and for the purpose specified.

In testimony where of, I have hereunto affixed my signature.

CHARLES J. DEL MARMOL.
